UNITED STATES PATENT OFFICE.

SAMUEL J. ELLIS, WILLIAM P. SMITH, AND HOMER G. WELLS, OF MEMPHIS,
TENNESSEE.

AUTOMATIC FREIGHT-CAR LOCK.

Application filed May 11, 1923. Serial No. 638,394.

To all whom it may concern:

Be it known that we, SAMUEL J. ELLIS, WILLIAM PRESTON SMITH, and HOMER G. WELLS, citizens of the United States, residing at Memphis, in the county of Shelby and State of Tennessee, have invented certain new and useful Improvements in Automatic Freight-Car Locks, of which the following is a specification.

10 Our said invention relates to an automatic lock for freight car doors and it is an object of the same to provide means whereby an additional seal is applied to freight car doors in a manner to insure that the door 15 cannot be opened without breaking a seal and calling attention to the condition of the car.

20 A further object of the invention is to provide a door of the character described 25 with means for holding it in either open or closed position.

Still another object is to do away with the necessity for applying cleats to the doors of freight cars to prevent them from opening due to rough handling or by reason of breakage of the ordinary fastenings. Our invention provides in effect an automatic cleat, which also prevents loss of doors by sliding off the guides.

30 Referring to the accompanying drawings, which are made a part hereof and on which similar reference characters indicate similar parts,

Figure 1 is a perspective of a freight car with the device of our invention applied thereto;

Figure 2, an elevation on an enlarged scale of a part of the car;

Figure 3, a horizontal section of Figure 40 2; and

Figure 4, a section on line 4—4 of Figure 3.

In the drawings reference character 10 indicates a freight car of conventional form having a door 11 slidably supported at its upper end. Such a door is usually provided at its forward side with a hasp and staple, or analogous locking device, indicated conventionally at 11', to which is attached a seal whereby an indication is given should the car be entered by opening the door, as in such case the seal will be broken. It is possible, however, to enter and rob a car without breaking the seal as, for

example, by removing the door guide at 55 the rear end of the door. The door is then sprung out and after robbery of the car, the guide is replaced and the robbery is not discovered until the car arrives at its destination. In such case there is no way 60 of determining where the robbery occurred as the seal is still intact. Another method frequently employed by thieves consists in raising the door over or out of the guides at the lower end thereof and then springing 65 the door away from the car at the lower corner farthest from the lock so as not to disturb the hasp and the seal.

To prevent unauthorized entry into the car without the leaving of traces we add 70 to the ordinary hasp and seal a lock attached to the lower end of the door and preferably near the lower rear corner, this position being especially effective to prevent the raising of the door off the lower 75 guide without breaking the seal. In the drawing I have shown a lock indicated generally at 12 and comprising a strap 13 secured by rivets, or the like, to the door 11, and a second strap 14 pivotally connected to the first by a pin 15 extending through eyes on the two parts. The strap 13 is bent down about the end of the door as shown in Fig. 3 and a spring 16 is coiled about the pin near its ends, washers 17 being inserted between the spring and the headed ends of the pin. The extreme ends of the spring are bent toward each other and rest against the bent part of the strap 13, while the middle portion of the spring lies 80 on the strap 14. In this manner we provide means for pressing the strap 14 strongly 85 toward the side of the car. A handle 18 is provided on the strap 14 for lifting the strap away from the car.

At the free end the strap 14 is bent toward the side of the car to form a tongue 19 adapted to enter a depression in the side of the car. This depression is provided by cutting out a part of the side and inserting therein a fitting 20 provided at opposite sides of the tongue with openings 21 extending from the outer face of the fitting 20 and curved toward each other so as to provide passages 22 opening into the space occupied by the tongue just above the tongue as indicated in Figs. 3 and 4. A seal of the ordinary type is inserted through

one of the openings 21 and forced through the two passages and through the passage in the tongue, or over the tongue if the same is made of sheet metal by stamping or die-casting, after which the ends are connected in the usual manner to seal the car.

A deeper depression in the fitting 20 provides a space to receive a pair of tongues 23 extending at right angles to tongue 19 and spaced thereby, said tongues supporting between them a roller 24. The tongues 23 and the roller co-operate with the depression in the fitting to provide a latch for holding the door in position and this latch is made automatic in its action by the spring 16.

In order to latch the door in either open or closed position a fitting 25, similar to fitting 20, is provided near the rear of the car, and to prevent wear on the side of the car by the travel of the spring-pressed latch, a metallic strap 26 is secured to the car between the two fittings. It will be seen that when the door is slid open the latch will hook into the depression in the fitting 25 in the same manner as in the fitting 20 and this is of use to prevent the door from sliding back and forth as the car is started and stopped or tilted up and down in traveling.

It will be obvious to those skilled in the art that our device may be modified in many ways without departing from the spirit of the invention, and therefore we do not limit ourselves to what is shown in the drawings and described in the specification, but only as indicated in the appended claims.

Having thus fully described our said invention, what we claim as new and desire to secure by Letters Patent, is:

1. A fastening device for freight car doors comprising a member for attachment to the car door, a swingable member hinged to said first mentioned member and adapted to be normally held in position to ride against the side of the car, and means adapted to be secured in the side of the car to receive a portion of said swingable member for securing the door in a predetermined position, substantially as set forth.

2. A fastening device for freight car doors comprising a member for attachment to the car door, a swingable member hinged to said first mentioned member and adapted to be normally held in position to ride against the side of the car, and a fitting in the side of the car providing a socket for a portion of said swingable member for securing the door in a predetermined position, said fitting and swingable member having apertures for the reception of a seal, substantially as set forth.

3. In a freight car, a spring-pressed latch moving with the door, means to co-operate therewith for holding the door in closed position, means to co-operate therewith for holding the door in open position, and a

strap extending between said means on which the end of the latch may travel, substantially as set forth.

4. A fastening device for freight car doors comprising a member for attachment to the door, a swingable member hinged to said first mentioned member and adapted to be normally held in position to ride against the side of the car, said member having a handle for releasing said door, a socket member on the car for engagement with the swingable member for securing the door in a predetermined position, substantially as set forth.

5. In a freight car having a sliding door with locking means at its forward edge, a lock at the rear edge of the door comprising a hinged member secured to the door, a bearing element carried by said hinged member, and means on the car whereby a sliding connection may be made between the car and the bearing element, substantially as set forth.

6. A lock for freight car doors comprising a strap for connection to the door, a member hinged to the strap having a tongue at its free end, a fitting on the car providing a socket to receive said tongue, and means on the fitting whereby a seal may be applied to hold the end of the tongue, substantially as set forth.

7. In a freight car door, a lock comprising a strap for attachment to the door, a member hinged thereto for movement toward and from the side of the car, a spring pressing said member toward the car, a latch at the free end of the member, and a fitting secured to the side of the car providing a socket to receive said latch, substantially as set forth.

8. In a freight car door, a lock comprising a strap for attachment to the door, a member hinged thereto for movement toward and from the side of the car, a spring pressing said member toward the car, a latch at the free end of the member, a fitting secured to the side of the car providing a socket to receive said latch, and a handle on the hinged member for withdrawing the latch from said engagement, substantially as set forth.

9. In a freight car door, a lock comprising a strap for attachment to the door, a member hinged thereto for movement toward and from the side of the car, a spring pressing said member toward the car, a latch at the free end of the member, a fitting secured to the side of the car providing a socket to receive said latch, a handle on the hinged member for withdrawing the latch from said engagement, a tongue at the free end of the latch, and guiding means on the fitting for locating a seal to secure said tongue, substantially as set forth.

10. In a freight car door, a lock comprising

ing a strap for attachment to the door, a member hinged thereto for movement toward and from the side of the car, a spring pressing said member toward the car, a latch at the free end of the member, a roller on the latch, and a fitting secured to the side of the car providing a socket to receive said latch, substantially as set forth.

11. In a freight car door, a lock comprising a strap for attachment to the door, a member hinged thereto for movement toward and from the side of the car, a spring pressing said member toward the car, a latch at the free end of the member, a roller on the latch, a fitting secured to the side of the car providing a socket to receive said latch, a second fitting near the rear end of the car to receive the latch for locking the door in open position, and a track between said fittings on which said roller travels, substantially as set forth.

12. In a freight car door, a lock comprising

ing a part secured to the door, a member hinged thereto having at its forward end tongues extending at right angles to the body of said member, a roller supported between said tongues, an intermediate tongue projecting in the direction of the body, and a fitting attached to the side of the car having a socket to receive the roller and also having a depression with opposed lateral passages leading therefrom through which a seal may be inserted through the tongue, substantially as set forth.

In witness whereof, we have hereunto set our hands and seals at Memphis, Tennessee this 30th day of April, A. D. nineteen hundred and twenty-three.
